COMBINED SCRAP BUNCH AND TURRET
MOLDING MACHINEJohn Fredrik Halstead, Brooklyn, N. Y., assignor
to International Cigar Machinery Company, a
corporation of New Jersey.Application December 30, 1931
Serial No. 583,973

21 Claims. (Cl. 131—9)

This invention relates to combined scrap bunch forming and shaping machines, its main object being to provide novel means for automatically removing a cover from one of the bunch shaping pockets of a cigar bunch shaping machine and serving it with a cigar bunch simultaneously from the rolling table of a scrap bunch forming machine, thereby combining them into a single self-contained piece of apparatus. With these 10 and other objects not specifically mentioned in view, the invention consists in certain constructions and combinations hereinafter fully described and then specifically set forth in the claims hereunto appended.

15 With two independently operated separate machines for bunch forming and bunch shaping, it is necessary to transfer the rolled bunch by hand from the rolling table of the bunch machine into one of the pockets of the bunch shaping turret, which operation is often performed unsatisfactorily by even an experienced operator. The novel cover removing and bunch transferring means, hereinafter described, not only dispenses with this service of an operator, but 20 locates the bunch properly in the bunch shaping pocket so that better shaped cigars result from its use.

This novel means consists in the combination of a pair of vertically swinging transfer arms 30 which receive the bunch from the rolling table and carry it into position for further manipulation; of a pair of locators which close up on the bunch when in manipulating position and properly position the same in the transfer arms 35 and point up the ends of the same; of a lifter which raises the located bunch; and of a horizontally swinging head having two arms and pivoted on a vertically reciprocating shaft which receives the bunch in a pocket in the bottom of one arm, raises it, then swings it into registration with a bunch shaping pocket in the turret, lowers it to the latter, and expels it into the pocket, while a cam-operated slide in the other 40 arm engages the cover of said pocket, locks the same to the arm, raises it and swings it out of the way of the incoming bunch, to be returned into position and unlocked as the first arm swings back into bunch receiving position.

45 In the accompanying drawings:

Fig. 1 is a side elevation of the automatic cover removing and bunch transferring means arranged to receive a bunch from the rolling table of a bunch forming machine and deliver it to the 50 turret of a bunch shaping machine;

Fig. 2 is an end elevation of the same, seen from line 2—2 of Fig. 1;

Fig. 3 is a detail top view of the bunch locator and of the bunch lifter including the actuating mechanism of the former, taken on line 3—3 of Fig. 2;

Fig. 4 is a detail top view, taken on line 4—4 of Fig. 1, showing the relative position of the bunch rolling table, bunch shaping turret, and the cover removing and bunch transferring means 65 in the bunch receiving position of the latter; and

Fig. 5 is a similar view with said means in its bunch delivery position.

In carrying the invention into effect there is 70 provided a device for rolling a binder about a charge of tobacco to form a bunch, an intermittently rotating turret having a plurality of bunch shaping pockets and a cover for each of 75 said pockets, means for simultaneously removing a cover from one of the pockets and swinging into position overlying said pocket, mechanism for ejecting the bunch from said means into the pocket, and bunch transferring mechanism receiving a bunch from said device and 80 delivering it to said means. In the best forms of construction contemplated, said means includes a head having a pair of arms, means on one arm 85 for receiving the bunch, means on the other arm for engaging the cover, and means for lifting, turning, and lowering said head. All the above 90 mentioned means and parts may be widely varied in construction within the scope of the claims, for the particular machine selected to illustrate the invention is but one of many possible concrete embodiments of the same. The invention, therefore, is not to be restricted to the precise 95 details of the machine shown and described.

Referring to Figs. 1, 2, and 3, the base 10, which joins the scrap bunch-rolling machine with the 95 bunch shaping machine, carries a pedestal 11 and a bearing frame 12. On shaft 13 pivoted in lugs 14 of pedestal 11 swing two bunch transfer arms 15, actuated by means of a crank 16 and a connecting rod 17 from a cam, not shown. The function of these arms is to receive the newly rolled bunch from the rolling table of the bunch shaping machine and to carry it into position for insertion into pocket provided for this purpose in the bottom of the bunch carrying arm, herein- 100 after described. The bunch receiving ends of the arms 15 have a solid jaw 18 and a resilient jaw 19 which is pressed by a spring 20 against an adjustable set screw 21 in the integral jaw so that 105 the opening of the empty jaws can be adjusted to 110

the proper distance, somewhat smaller than the diameter of the bunch.

Vertical rods 22, guided in bearings 23 and 24 of pedestal 11 and actuated by a connecting bracket 25, a link 26 and a lever 27 from another cam not shown, operate the bunch lifter 28 which consists of a base secured to the upper ends of the rods 22 and carrying on bent arms a central and two outer blocks concaved to fit the shape of the bunch and designed for removing the latter from the transfer arms 15.

On horizontal rods 29 supported in a block 30 carried by a post 31 of pedestal 11 slide the locators 32, the bunch positioning ends of which have tapered depressions so as to shape or point up the ends of the bunch when closing up on the same. The locators 32 have inward projections 33 against which the jaws 19 of arms 15 rest in their bunch delivery position and which serve as guides for the bunch when raised by the lifter from the transfer arms. The locators 32 have horizontally projecting pins 34 through which they are actuated by levers 35 pivoted on studs 36 of pedestal 11, the levers 35 being connected by a bar 37 and actuated by a rod 38 pivoted to a stud 39 on an arm 40 of one of them. The rod 38 is operated from a cam, not shown.

In bearings 41 and 42 of frame 12 is slidably but non-turnably supported a vertical shaft 43 on which is loosely mounted a head 44 carrying two arms 45 and 46 at right angles to one another. The collar 47 fixed on shaft 43 normally rests on the bearing 41. When in this position, another fixed collar 48, having a tapered cam projection 49 extending radially from it in the direction of turret 81, rests on the head 44 which is supported in its lowermost position by one of two set screws 50, 50' carried in radial projections 51 of head 44 and resting on a horizontal projection of a guide bar 52 inserted in the bearing frame 12, see Figs. 1, 4, and 5. Thus, when the shaft 43 is raised by the rod 53 actuated from a cam, not shown, and pivotally attached to shaft 43 by means of socket joints 54 and 55 connected by a stud 56, it will first lift the collar 48 from the head 44 and then, after the collar 47 has come into contact with the bottom of head 44, will raise the head with its arms 45 and 46.

In radially projecting lugs 57, the head 44 carries a vertical rod 58 with which engages a forked block 59 turnably carried by one arm of a bell-crank lever 60 pivoted on a stud 61 in bearing frame 12 and held in place by a collar 62. The other arm 63 of lever 60 is connected by a stud 64 to a rod 65 actuated by a cam, not shown. By moving the lever 60 from one position to the other, the fork 59 turns the head 44 through 90 degrees, thereby moving the arm 45 into the position formerly occupied by arm 46 and vice versa. In order to effect accurate registration of these arms with the bunch locator and with the turret mold respectively, the projections 51 of the head 44 are equipped with adjustable rollers 66 which in the extreme horizontal positions of the head 44 engage with one or the other side of bar 52 and guide the head in its vertical movement. The rollers 66 are fastened to the head by means of eccentric studs 67 so that the horizontal throw of the head can be accurately adjusted. All the cams used for producing the various movements of the transfer mechanism are driven in synchronism with the bunch forming and shaping machines, the drives of which are inter-connected.

The arm 45 at its bottom carries a pocket 68, formed by slightly spaced walls having concave

cavities, for the reception of the bunch which is forced thereinto from the locators 32 by the lifter 28 and retained therein by frictional cohesion and the pressure of said walls. On its top, the arm 45 has a boss 69 in which are guided two vertical pins 70 joined at their upper ends by a yoke 71 held in its up-position by a spring 72. On yoke 71 rests a roller 73 carried by one arm of a bell crank lever 74 pivoted on a stud 75 in lugs 76 of head 44. The other arm of lever 74 carries a roller 77 adapted to engage with the tapered cam projection 49 of collar 48 when arm 45 is in the bunch delivery position shown in Fig. 5. When this engagement takes place on the descent of shaft 43 relative to head 44, while the latter is supported by the set screw 50, the lever 74 is turned into position 74'', Fig. 2, and the roller 73 depresses yoke 71 into position 71'', thereby causing the pins 70 to eject the bunch from pocket 68.

The arm 46 at its bottom has two lugs 78 provided with transverse channels, Fig. 1, adapted to engage rollers 79 provided at the ends of each mold cover 80 on the intermittently rotating bunch shaping turret 81 as each cover reaches its uppermost position. The details of the turret and indexing device for intermittently rotating the turret are shown in the copending application of Rupert E. Rundell, Ser. No. 185,199, filed April 20, 1927, to which reference is made for a complete disclosure of the same. Each cover has two axially grooved radial upward projections 83, Figs. 1 and 4, and the arm 46 has a longitudinal slide 84 with two aligned downward projections 85 and 85' adapted to be engaged with the axial grooves in projections 83 by the action of a coil spring 86 stretched from a post 87 in arm 46 to a post 88 in slide 84. In the lowermost position of shaft 43, the slide 84 is kept out of engagement with cover 80 by a lever 89 pivoted on stud 90 in lugs 91 of head 44 and held in position by a roller 92 engaging with the tapered cam projection 49 of collar 48 when arm 45 is in the bunch receiving position shown in Fig. 4. When disengagement of roller 92 and tapered cam projection 49 takes place on the ascent of shaft 43 relative to head 44, the spring 86 thus released causes the slide 84 to move into its engagement position 84' and thereby to lock cover 80 to arm 46, as shown in Fig. 5 and in dotted lines in Fig. 1.

The operation of the device is as follows: When the turret rotates, the shaft 43 is in its lowermost position with the set screw 50 of head 44 resting on guide bar 52 and the arms 45 and 46 in their receiving positions as shown in Fig. 4, the roller 66 being in contact with guide bar 52. Upward motion of rod 17 then causes the arms 15 to swing into their delivery position 15', shown in Figs. 1 and 2, in which the bunch B, which has previously been deposited into their jaws by the chianti belt 93 as the latter had reached its end position on rolling table 94 by the motion of rolling pin 95, registers with the locators 32. As the chianti belt, rolling table, and rolling pins are parts of a scrap bunch forming mechanism of well known construction, further description of the same is unnecessary. The locators are then moved toward the bunch into the dotted position 32' shown in Fig. 2, by the action of rod 38, thus pointing up the ends 145 of the bunch and positioning it for proper entrance into pocket 68 of arm 45, into which the bunch is now inserted by the motion of lever 27 raising the lifter 28. While the lifter rests in its up-position, the rod 53 begins its upward

- motion, the carrier shaft 43 first ascending alone, releasing roller 92, which in the bunch receiving position of the arms is in engagement with cam projection 49, and thereby locking the cover 80 to arm 46, and then taking the head 44 with it by means of collar 47, the collar 48 in the uppermost position 43' of the shaft being in position 48', Figs. 1 and 2. The arm 45 by this motion of rod 53 has reached the position 45', Fig. 2, with yoke 71 and lever 74 in unchanged relative positions 71' and 74'. During the ascent of head 44, the bunch lifter 28 descends and the locators 32 move apart into their original positions.
- 15 Next, the rods 17 and 65 are actuated, the former returning arms 15 into their bunch receiving position at the rolling table 94, and the latter swing the arms 45 and 46 from the position shown in Fig. 4 to that shown in Fig. 5. With 20 the arms in the latter position in which roller 66' contacts with bar 52, the rod 53 descends, first lowering shaft 43 and the arms so that arm 45 now is in delivery position above the open pocket of the turret mold 80, Fig. 5, and then, 25 when the set screw 50' has come to rest on guide bar 52, lowering shaft 43 alone so that the tapered cam projection 49 of collar 48, which in the delivery position of the head registers with arm 45, turns the lever 74 into position 74'', Fig. 30 2, thereby depressing the yoke 71 into position 71'' and ejecting the bunch from the pocket 63 in the mold 80. The descent of the shaft 43 does not affect the roller 92 because the arm 46 in this position of head 44 does not register with taper 49.
- 35 Having inserted the bunch B into the uppermost mold pocket of the turret mold, the carrier shaft 43 again ascends, first alone, lifting collar 48 from head 44, whereby the lever 74 is released and the ejecting pins 70 are raised by spring 72, and then, when the collar 47 has engaged head 44, with the arms 45 and 46. When 40 in uppermost position, clear of the covers of the closed mold pockets, the arm 45 is swung back into bunch receiving position and the shaft 43 is lowered. This brings cover 80, which during the 45 insertion of the bunch B into the pocket of turret 81 was held out of the way by arm 46, back into position on the turret, the final downward movement of the shaft 43 returning the taper 49 into engagement with the roller 92, thereby 50 unlocking the cover from the arm. This final movement of shaft 43 has no effect on lever 74 on arm 45 because roller 77 in the bunch delivery position of the arms is 90 degrees away from taper 49.
- 55 While the cover is replaced over the bunch B just inserted into the turret, the rolling pin 95 which, during the inward movement of arms 15 and during the operation of the locators 32 and lifter 28, has been at rest at the far end of rolling table 94 to allow a new charge to be measured in the scrap bunch machine and deposited onto the chianti belt 93, and which during the transfer movement of the arms has rolled this charge into a bunch, ejects the new bunch into the jaws of arms 15 and returns into resting position at the far end of the rolling table.
- 60 The replaced mold cover being held in place by means, not shown, incorporated with the turret, the latter is now ready to index for the locating of the next bunch shaping pocket.
- 65 What is claimed is:
- 70 1. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means.
- 75 2. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means, said means including a head, an arm on said head, means on said arm for engaging the cover at said station, and means for lifting, swinging, and lowering said head, whereby the cover is lifted and swung away from its pocket and then replaced.
- 80 3. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means, said means including a head, an arm on said head having a cavity on its bottom adapted to receive and retain a bunch, and means for lifting, turning, and lowering said head to move the bunch in said cavity into a position overlying said pocket.
- 85 4. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means.
- 90 5. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means.
- 95 6. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means.
- 100 7. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means.
- 105 8. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means.
- 110 9. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means.
- 115 10. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means.
- 120 11. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means.
- 125 12. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means.
- 130 13. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means.
- 135 14. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means.
- 140 15. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means.
- 145 16. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means.
- 150 17. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means.

- means, said means including a reciprocating shaft, a head loosely mounted on said shaft, an arm on said head having a cavity on its bottom adapted to receive and retain a bunch, a collar fixed to said shaft below said head to lift and lower it, means for turning said head to swing the bunch in said cavity into a position overlying said pocket, and said ejecting mechanism including ejector pins mounted in said arm to enter said cavity, a yoke connecting the outer ends of said pins, a spring interposed between said yoke and arm, a bell crank lever pivoted on said head and engaging said yoke, and a tapered cam projection fixed on said shaft above said head to engage said lever on the downward stroke of said shaft, when the bunch in said cavity is in a position overlying said pocket, to urge the pins into said pocket to eject the bunch therefrom.
5. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means, said means including a head, an arm on said head, means on said arm to engage the cover at said station of said turret and lock it on said arm, means for lifting, turning and lowering said head, and means to unlock said cover from said arm.
- 40 6. The combination with a device for rolling a binder about a charge of tobacco to form a bunch, of an intermittently rotating turret having a plurality of bunch shaping pockets and a cover for each of said pockets, vertically reciprocating and horizontally oscillating means for simultaneously lifting vertically a cover at one station of said turret and a bunch and then horizontally swinging said cover and bunch to simultaneously swing the cover away from its pocket and swing the bunch into a position overlying said pocket, mechanism for ejecting the bunch from said means into said pocket while the bunch is in a position overlying said pocket, and bunch transferring mechanism for receiving a bunch from said device and delivering it to said means, said means including members for swinging the bunch into position to be delivered to said means, devices for locating the bunch on said members in the proper position to be delivered to said means and simultaneously pointing up the ends of the bunch, and means for removing the bunch from said members and delivering it to said means.
- 45 7. The combination with an intermittently rotating turret having a plurality of bunch shaping pockets and a cover for each of said pockets, of vertically reciprocating and horizontally oscillating means for simultaneously lifting vertically a cover at one station of said turret and a bunch and then horizontally swinging said cover and bunch to simultaneously swing said cover away from its pocket and swing the bunch into a position overlying said pocket, and mechanism for ejecting the bunch from said means into said

90 pocket while the bunch is in a position overlying said pocket.

8. The combination with an intermittently rotating turret having a plurality of bunch shaping pockets and a cover for each of said pockets, of vertically reciprocating and horizontally oscillating means for simultaneously lifting vertically a cover at one station of said turret and a bunch and then horizontally swinging said cover and bunch to simultaneously swing said cover away from its pocket and swing the bunch into a position overlying said pocket, and mechanism for ejecting the bunch from said means into said pocket while the bunch is in a position overlying said pocket, said means including a head, an arm on said head, means on said arm for engaging the cover at said station, and means for lifting, turning, and lowering said head, whereby the cover is lifted and swung away from its pocket and then replaced.

9. The combination with an intermittently rotating turret having a plurality of bunch shaping pockets and a cover for each of said pockets, of vertically reciprocating and horizontally oscillating means for simultaneously lifting vertically a cover at one station of said turret and a bunch and then horizontally swinging said cover and bunch to simultaneously swing said cover away from its pocket and swing the bunch into a position overlying said pocket, and mechanism for ejecting the bunch from said means into said pocket while the bunch is in a position overlying said pocket, said means including a head, an arm on said head having a cavity on its bottom adapted to receive and retain a bunch, and means for lifting, turning, and lowering said head to move the bunch in said cavity into a position overlying said pocket.

10. The combination with an intermittently rotating turret having a plurality of bunch shaping pockets and a cover for each of said pockets, of vertically reciprocating and horizontally oscillating means for simultaneously lifting vertically a cover at one station of said turret and a bunch and then horizontally swinging said cover and bunch to simultaneously swing said cover away from its pocket and swing the bunch into a position overlying said pocket, and mechanism for ejecting the bunch from said means into said pocket while the bunch is in a position overlying said pocket, said means including a reciprocating shaft, a head loosely mounted on said shaft, an arm on said head having a cavity on its bottom adapted to receive and retain a bunch, a collar fixed to said shaft below said head to lift and lower it, means for turning said head to swing the bunch in said cavity into a position overlying said pocket, and said ejecting mechanism including ejector pins mounted in said arm to enter said cavity, a yoke connecting the outer ends of said pins, a spring interposed between said yoke and arm, a bell crank lever pivoted on said head and engaging said yoke, and a tapered cam projection fixed on said shaft above said head to engage said lever on the downward stroke of said shaft, when the bunch in said cavity is in a position overlying said pocket, to cause said pins to eject the bunch therefrom.

11. The combination with an intermittently rotating turret having a plurality of bunch shaping pockets and a cover for each of said pockets, of vertically reciprocating and horizontally oscillating means for simultaneously lifting vertically a cover at one station of said turret and a bunch and then horizontally swinging said cover and

- 5 bunch to simultaneously swing said cover away from its pocket and swing the bunch into a position overlying said pocket, and mechanism for ejecting the bunch from said means into said pocket while the bunch is in a position overlying said pocket, said means including a head, an arm on said head, means on said arm to engage the cover at said station of said turret and lock it on said arm, means for lifting, turning, and lowering said head, and means to unlock said cover from said arm. 10
12. The combination with an intermittently rotating turret having a plurality of bunch shaping pockets and a cover for each of said pockets, of vertically reciprocating and horizontally oscillating means for simultaneously lifting vertically a cover at one station of said turret and a bunch and then horizontally swinging said cover and bunch to simultaneously swing said cover away from its pocket and swing the bunch into a position overlying said pocket. 15
13. The combination with an intermittently rotating turret having a plurality of bunch shaping pockets and a cover for each of said pockets, of vertically reciprocating and horizontally oscillating means for simultaneously lifting vertically a cover at one station of said turret and a bunch and then horizontally swinging said cover and bunch to simultaneously swing said cover away from its pocket and swing the bunch into a position overlying said pocket, said means including a head, an arm on said head, means on said arm to engage the cover at station of said turret and lock it on said arm, means for lifting, turning, and lowering said head, and means to lock and unlock said cover on said arm. 20
14. The combination with an intermittently rotating turret having a plurality of bunch shaping pockets and a cover for each of said pockets, of vertically reciprocating and horizontally oscillating means for simultaneously lifting vertically a cover at one station of said turret and a bunch and then horizontally swinging said cover and bunch to simultaneously swing said cover away from its pocket and swing the bunch into a position overlying said pocket, said means including a head, an arm on said head having a cavity on its bottom adapted to receive and retain a bunch, and means for lifting, turning, and lowering said head to move the bunch in said cavity into said predetermined position. 25
15. Means for removing a cover from a cigar bunch shaping pocket, comprising a head, an arm on said head, means on said arm for engaging the cover, and vertically reciprocating and horizontally oscillating means for lifting, turning, and lowering said head, whereby the cover is lifted, swung away, and then replaced. 30
16. Means for removing a cover from a cigar bunch shaping pocket, comprising a head, an arm on said head, means on said arm to engage the cover and lock it on said arm, vertically reciprocating and horizontally oscillating means for lifting, turning, and lowering said head, and means to lock and unlock said cover on said arm. 35
17. Means for moving a cigar bunch into a predetermined position, comprising a head, an arm on said head having a cavity on its bottom adapted to receive and retain a cigar bunch, and means for lifting, turning, and lowering said head to move the bunch in said cavity into said predetermined position. 40
18. Means for moving a cigar bunch into a predetermined position, comprising a head, an arm on said head having a cavity on its bottom adapted to receive and retain a cigar bunch, and means for lifting, turning, and lowering said head to move the bunch in said cavity into said predetermined position, and means for ejecting the bunch from said cavity. 45
19. Bunch transferring mechanism including members for swinging a cigar bunch into a predetermined position, devices for locating the bunch endwise on said members and simultaneously shaping the ends only thereof into wedge form, and means for ejecting the bunch from said members. 50
20. The combination with a bunch rolling table, of a rotating turret having a plurality of bunch shaping pockets, means for successively transferring bunches from said table to said pockets, and mechanism for locating the bunches endwise to center them in said means, said means including a lifter operating to eject the bunch from said mechanism while it is held by said mechanism in centered position. 55
21. The combination with a bunch rolling table, of a rotating turret having a plurality of bunch shaping pockets, means for successively transferring bunches from said table to said pockets, and mechanism for shaping the bunch ends only into wedge form while in said means. 60
22. The combination with a bunch rolling table, of a rotating turret having a plurality of bunch shaping pockets, means for successively transferring bunches from said table to said pockets, and mechanism for shaping the bunch ends only into wedge form while in said means. 65
23. The combination with a bunch rolling table, of a rotating turret having a plurality of bunch shaping pockets, means for successively transferring bunches from said table to said pockets, and mechanism for shaping the bunch ends only into wedge form while in said means. 70
24. The combination with a bunch rolling table, of a rotating turret having a plurality of bunch shaping pockets, means for successively transferring bunches from said table to said pockets, and mechanism for shaping the bunch ends only into wedge form while in said means. 75
25. The combination with a bunch rolling table, of a rotating turret having a plurality of bunch shaping pockets, means for successively transferring bunches from said table to said pockets, and mechanism for shaping the bunch ends only into wedge form while in said means. 80
26. The combination with a bunch rolling table, of a rotating turret having a plurality of bunch shaping pockets, means for successively transferring bunches from said table to said pockets, and mechanism for shaping the bunch ends only into wedge form while in said means. 85
27. The combination with a bunch rolling table, of a rotating turret having a plurality of bunch shaping pockets, means for successively transferring bunches from said table to said pockets, and mechanism for shaping the bunch ends only into wedge form while in said means. 90
28. The combination with a bunch rolling table, of a rotating turret having a plurality of bunch shaping pockets, means for successively transferring bunches from said table to said pockets, and mechanism for shaping the bunch ends only into wedge form while in said means. 95
29. The combination with a bunch rolling table, of a rotating turret having a plurality of bunch shaping pockets, means for successively transferring bunches from said table to said pockets, and mechanism for shaping the bunch ends only into wedge form while in said means. 100
30. The combination with a bunch rolling table, of a rotating turret having a plurality of bunch shaping pockets, means for successively transferring bunches from said table to said pockets, and mechanism for shaping the bunch ends only into wedge form while in said means. 105
31. The combination with a bunch rolling table, of a rotating turret having a plurality of bunch shaping pockets, means for successively transferring bunches from said table to said pockets, and mechanism for shaping the bunch ends only into wedge form while in said means. 110
32. The combination with a bunch rolling table, of a rotating turret having a plurality of bunch shaping pockets, means for successively transferring bunches from said table to said pockets, and mechanism for shaping the bunch ends only into wedge form while in said means. 115
33. The combination with a bunch rolling table, of a rotating turret having a plurality of bunch shaping pockets, means for successively transferring bunches from said table to said pockets, and mechanism for shaping the bunch ends only into wedge form while in said means. 120
34. The combination with a bunch rolling table, of a rotating turret having a plurality of bunch shaping pockets, means for successively transferring bunches from said table to said pockets, and mechanism for shaping the bunch ends only into wedge form while in said means. 125
35. The combination with a bunch rolling table, of a rotating turret having a plurality of bunch shaping pockets, means for successively transferring bunches from said table to said pockets, and mechanism for shaping the bunch ends only into wedge form while in said means. 130
36. The combination with a bunch rolling table, of a rotating turret having a plurality of bunch shaping pockets, means for successively transferring bunches from said table to said pockets, and mechanism for shaping the bunch ends only into wedge form while in said means. 135
37. The combination with a bunch rolling table, of a rotating turret having a plurality of bunch shaping pockets, means for successively transferring bunches from said table to said pockets, and mechanism for shaping the bunch ends only into wedge form while in said means. 140
38. The combination with a bunch rolling table, of a rotating turret having a plurality of bunch shaping pockets, means for successively transferring bunches from said table to said pockets, and mechanism for shaping the bunch ends only into wedge form while in said means. 145
39. The combination with a bunch rolling table, of a rotating turret having a plurality of bunch shaping pockets, means for successively transferring bunches from said table to said pockets, and mechanism for shaping the bunch ends only into wedge form while in said means. 150
